UNITED STATES PATENT OFFICE.

PHILLIP HAMM, OF FOSTORIA, OHIO, ASSIGNR OF ONE-HALF TO JOSEPH N. KIRSCHNER, OF SAME PLACE.

TOBACCO-MOISTENER.

SPECIFICATION forming part of Letters Patent No. 430,643, dated June 24, 1890.

Application filed February 24, 1890. Serial No. 341,530. (No model.)

To all whom it may concern:

Be it known that I, PHILLIP HAMM, a citizen of the United States, residing at Fostoria, in the county of Seneca and State of Ohio, have invented certain new and useful Improvements in Tobacco-Moisteners; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an apparatus for moistening tobacco, and has for its object to provide an inexpensive, convenient, and effective attachment to a pail, cask, tub, showcase, or receptacle of any character for containing tobacco, whereby the same may be kept in a fresh and moist condition.

A further object is to provide a combined cover for the package and moistener for the contents thereof.

A further object is to provide a cover adapted to fit packages of different diameters.

The invention consists in the parts and combination of parts hereinafter described, and pointed out in the claims.

In the drawings, Figure 1 is a side elevation of an ordinary tobacco-package with my apparatus secured thereon. Fig. 2 is a top plan view of the same. Fig. 3 is a plan view of the apparatus as applied to a rectangular receptacle, the top of the receptacle for moistening being removed; and Fig. 4 is a longitudinal vertical sectional view of the upper portion of a tub with my apparatus secured thereon.

As is well known, it is necessary to keep tobacco in a moistened state to preserve its better qualities and render it fit for sale, for if permitted to become dry it loses flavor and pulverizes to a degree to render it almost worthless. It has been usual to moisten the tobacco by sprinkling the same; but this is attended with considerable care and tends to unevenly dampen the same.

Various devices have been employed by which to cause an evaporation from water to arise through the tobacco; but these are dif-

ficult of attention and moisten the part less exposed to atmospheric influences more than that from which the present demand is supplied.

I have sought to provide an apparatus that can be readily attached to a round or other shaped receptacle, and that will act as a closure to the same, and at the same time that will moisten the top of the tobacco in the package, that being the part most exposed to atmospheric influence, thereby keeping the tobacco in proper condition until entirely removed from the package.

A designates an ordinary tobacco pail or tub, from which the top is moved and the apparatus for moistening the same substituted therefor.

A' designates a cover, consisting of a stationary portion B, and a movable portion C, hinged at C' to the stationary portion.

D designates a depending flange extending from the greatest diameter of the cover, and E designates a like flange depending from the cover concentrically of the flange D, the flange E being preferably of greater width than that of flange D.

The construction described forms an annular channel F, into which the upper end of the package rests, thereby excluding the air from the same.

By reference to Fig. 4 it will be seen that by making the flange E of greater width than flange D the cover is adaptable to packages of different diameters, the lines x x of said figure illustrating the lower flange closing the receptacle when of a diameter corresponding to that height, and the extended portion above the lines x x showing the top and outer flange closing the package. This adaptability to close packages of different heights is one of great value when it is considered that the packages are not uniform in size.

G designates a catch, which may be either a spring-catch or hinged to the swinging part of the top, and adapted to be engaged with a catch G' upon flange D to close the top against the ingress of air.

H designates a receptacle for a moisture-retaining substance, preferably sponge, as shown at I, the receptacle being closed by a

removable cover J. The receptacle for moisture is in communication with the package in which the tobacco is contained by reason of the cover A being perforated within the area 5 of the receptacle, as at H.

In Fig. 3 is shown a construction adaptable to receptacles rectangular in form, the construction being the same with the exception of the contour.

10 In operation an original package of tobacco is opened and my apparatus placed as a cover thereon. The sponge is now moistened, preferably by a preparation consisting of simple sirup and glycerine, the evaporation of this 15 preparation being just sufficient to moisten the tobacco the desired amount. When it is desired to gain access to the package, the hinged portion C of the cover is raised, and when a sufficient quantity has been taken from the 20 package the portion C is closed and the catch engaged, thereby excluding the air.

It will be seen that the apparatus serves the purposes of a convenient cover and also as a moistener.

25 What I claim is—

1. The herein-described apparatus for moistening tobacco, consisting of a cover provided with two concentric flanges upon its under side, the inner flange being of greater width 30 than the outer flange, and a receptacle adapted to contain a moistening substance, located upon the upper side of the cover and in com-

munication with the contents of the package upon which the cover is placed, as and for the purpose set forth. 35

2. A tobacco-moistening apparatus consisting of a cover comprising a stationary portion and a movable portion, and provided with two concentric flanges upon its under side, the inner flange being of greater width 40 than the outer flange, and a receptacle adapted to contain a moistening substance, located upon the upper side of the stationary portion of the cover and in communication with the contents of the package upon which the cover 45 is placed, as and for the purpose set forth.

3. A tobacco-moistening apparatus consisting of a cover comprising a stationary portion and a hinged portion, and provided with two concentric flanges upon its under side, 50 the inner flange being of greater width than the outer flange, and a receptacle adapted to contain a moistening substance, located upon the upper side of the stationary portion of the cover and in communication with the 55 contents of the package upon which the cover is placed, as and for the purpose set forth.

In testimony that I claim the foregoing as my own I hereby affix my signature in presence of two witnesses.

PHILLIP HAMM.
